REGINALD BOYD WOODCOCK AND THOMAS AUBREY KESTELL, OF LEICESTER, ENGLAND,
ASSIGNORS TO UNITED SHOE MACHINERY CORPORATION, OF PATERSON, NEW
JERSEY, A CORPORATION OF NEW JERSEY

SOLE-ROUNDING MACHINE

Application filed February 19, 1926, Serial No. 89,415, and in Great Britain March 13, 1925.

This invention relates to sole rounding machines wherein a knife and a pattern are relatively movable to cause the point of operation of the knife to be transferred around the pattern. As herein illustrated the invention is embodied in a machine in which the pattern is stationary and the knife is caused to travel around the pattern although certain features of the invention are not restricted in their application to machines of this particular type but are capable of embodiment also in machines wherein the relative movement of the knife and the pattern is obtained by rotating the pattern.

An example of a sole rounding machine in which the knife travels around the pattern may be found in United States Letters Patent No. 882,009, granted March 17, 1908, on application of B. F. Mayo. The machine disclosed in this patent is provided with stop mechanism the construction and mode of operation of which is described in detail in United States Letters Patent No. 1,091,071, granted March 24, 1914, also on application of B. F. Mayo. This stop mechanism functions to allow the knife, after completing its circuit of the pattern, to continue a short distance beyond its starting point, under the momentum of the knife supporting means, to insure complete rounding of the sole, and then to move the knife in the opposite direction to return it to starting position, the return of the knife being effected by the reaction of a spring arranged to be stressed by the excess movement or overthrow of the knife supporting means.

One object of the present invention is to provide improved and simplified mechanism which will operate still more quickly and reliably to return the rounding knife to starting position at the completion of its excess or overthrow movement.

With this object in view one feature of this invention resides in the combination, in a rounding machine having a knife and a pattern which are relatively movable to transfer the point of operation of the knife around the pattern, of knife driving mechanism which is movable under momentum after being disconnected from its source of

power to effect excess relative movement of the knife and the pattern to carry the point of operation of the knife past the starting point, means normally disconnected from the knife driving mechanism for reversing the direction of relative movement of the knife and the pattern, and a device for connecting said means with the knife driving mechanism when the latter is disconnected from its source of power. As herein illustrated the means for reversing the direction of relative movement of the knife and the pattern comprises a spring, and this spring is adapted to be connected with a driving shaft by a clutch in such a way that the spring will first absorb the momentum of the knife driving mechanism during the overthrow of the knife and thereafter will react to return the knife to starting position. One member of the clutch is in the form of a drum on the driving shaft while the other clutch member consists of a split band which encircles the drum and is connected with a lever which controls the starting and stopping of the machine, the arrangement being such that when the lever is actuated to start the machine the band is released from the drum and when the lever is actuated to stop the machine the band is clutched to the drum. The illustrated arrangement embodies the further feature that a limiting stop is withdrawn from an abutment during the stressing of the spring and is moved into engagement with said abutment by the reaction of the spring to determine positively the position at which the knife shall come to rest at the end of its return movement.

In the machine disclosed in the Letters Patent first above referred to the rounding knife, at the completion of its excess or overthrow movement, rides along the edge of the pattern during its return movement and when it finally comes to rest it is still in contact with the pattern. It is sometimes desirable, however, and it has heretofore been proposed to move the knife away from the edge of the pattern during its return movement to set it at a point spaced from the pattern so that it may function as a gage to position a succeeding sole blank with the edge of the

blank properly overlapping the edge of the pattern at the point where the knife is to begin its cutting action.

With the foregoing in mind another object of the invention is to provide positively acting means for insuring that the knife, instead of following the contour of the pattern upon its return or retrograde movement, will part company with the pattern.

To this end, and in accordance with another feature of the invention, there is provided, in a sole rounding machine wherein a pattern and a knife are relatively movable to transfer the point of operation of the knife around the pattern and wherein there is further relative movement of the knife and the pattern under momentum to insure complete rounding of the sole, resilient means constructed and arranged to be stressed by said further relative movement to effect limited relative retrograde movement of the knife and the pattern at the end of a rounding operation, and automatic means operated by said retrograde movement for separating the knife and the pattern. In the illustrated embodiment of the invention the knife, which is arranged to travel around the pattern beyond the starting point and thereafter to return to the starting point, is mounted upon a knife support which is normally moved relatively to a moving carrier to hold the knife against the pattern as the knife is operating, and the separation of the knife and the pattern is effected by a means for locking the knife support to the carrier which means is rendered effective by the carrier moving means during the return movement of the knife.

The above and other objects and features of the invention will become apparent from the following description of the preferred embodiment of the invention illustrated in the accompanying drawings in which:

Fig. 1 is a view, partially in side elevation and partially in section, of a portion of the mechanism for effecting the return movement of the knife, and

Fig. 2 is a plan view of a portion of a sole rounding machine showing particularly the mechanism for retracting the knife from the pattern during the return movement of the knife.

In the drawings the invention is shown as embodied in a machine such as that disclosed in Letters Patent No. 882,009, hereinbefore referred to, and which in common with said machine comprises a stationary pattern indicated in dot and dash lines at 4 in Fig. 2, a rounding knife 6, a knife support consisting of an arm 8 rigidly secured to a segmental plate 10, a carrier 12 to which the plate 10 is pivotally connected, a rotary table or support 14 upon which the carrier 12 is slidably mounted for inward and outward movement relatively to the pattern, a cam

16 for imparting inward and outward movement to the carrier 12, a main driving shaft 18, and a frame, a portion of which is shown at 20 in Fig. 1, for supporting the various parts of the machine.

In the illustrated machine the construction of the operating parts above referred to and, except as hereinafter described, their mode of operation is substantially the same as that set forth in said patent to which reference may be had for a detailed description of parts or movements not herein fully shown or described. For present purposes, however, it will be sufficient to understand that as the knife travels around the pattern it is held yieldingly in engagement with the edge of the pattern by means of a spring-actuated pinion (not shown) which is confined within a housing 22, the pinion meshing with the teeth of a segmental rack 24 on the knife carrier 12.

The means which permits the knife to travel beyond its starting point after it has completed a circuit of the pattern and which causes the knife thereafter to be returned to its starting position comprises a drum 26 formed on the side of a wheel 28 which is fast upon the main shaft 18, the wheel 28 corresponding to the wheel $\frac{1}{2}$ of the above-mentioned Letters Patent No. 1,091,071. Encircling the drum 26 is a band 30 which is capable of being gripped to the drum. For this purpose one end of the band 30 is connected at 31 to a lever 32 pivoted at 33 to an arm 34 which is mounted to swing about the driving shaft 18. The other end of the band 30 is connected by an adjustable link 35 to the pivot 33 of the lever 32, the construction being such that if the lever 32 is rocked about its pivot the band 30 is gripped to or released from the drum 26 and when the band is gripped to the drum the arm 34 and the lever 32 will turn with the drum about the axis of the driving shaft 18.

Pivotedly connected to the arm 34 is one end of a plunger 36 slidably mounted in a tubular casing 38 pivoted about midway between its ends upon a horizontal pivot 40 on the machine frame. A spring 42 inside the casing 38 surrounds the plunger 36 and bears at one end on a head 44 formed on the end of the plunger remote from its pivotal connection and at the other end against a cap 46 of the casing, the arrangement being such that when the band 30 is clutched to the drum 26 the arm 34 moves with the drum and the spring 42 is compressed. An opening 48 is formed in the side of the casing 38 in such a position that upon the return movement of the plunger 36 the head 44 of the plunger 36, which is a close sliding fit in the casing 38, forces the air within the cylinder out through the opening 48 freely until the head passes the opening 48, thus trapping a small quantity of air in the closed end of the casing,

allowing the plunger to seek its extreme position only as fast as the air escapes past the head of the plunger. By this means a dash pot is provided gradually to arrest the return movement of the plunger, thereby cushioning the reverse movement of the knife driving mechanism.

The lever 32 is swung about its pivot 33 in a direction to clutch the band 30 to the drum 26 by a spring 50 connected to said lever and to the arm 34. The lever 32 is swung in the opposite direction by a bell-crank lever 52 pivoted at 54 on the frame 20 of the machine, the bell-crank lever having one arm arranged to engage the lever 32 and another arm connected to a starting lever 56 corresponding to the lever *n* of the machine shown in the aforementioned Letters Patent No. 1,091,071.

When the starting lever 56 is actuated by the operator to start the machine the lever 32 is swung about its pivot 33 by the bell-crank lever 52 to release the band 30, and when the starting lever is automatically released and returned to stop the machine the lever 32 is swung in the opposite direction by its spring 50 to clutch the band 30 to the drum 26 and during the continued movement of the rounding knife mechanism under its own momentum the spring 42 of the plunger 36 is compressed and gradually stops the knife mechanism. The spring 42 then expands and returns the knife to its starting position, a collar 58 fixed on the plunger 36 engaging the cap 46 on the casing 38 to limit the return movement of the plunger.

During its return movement the knife is prevented from returning along the edge of and in contact with the edge of the pattern 4 and the trimmed sole thereon by mechanism (Figure 2) which locks the segmental plate 10 to the carrier 12 so that said plate is prevented from being swung about its pivotal connection with said carrier by the spring-actuated pinion within the housing 16 as said carrier is moved back to starting position as hereinbefore described. The return movement of the carrier 12 is in such a direction that with the plate 10 thus locked to the carrier the knife will be moved away from the sole edge into position to act as a gage for a fresh blank. A fresh blank may then readily be placed in the machine with its edge overlapping the pattern all the way round without the necessity of manually withdrawing the knife.

The mechanism just referred to for preventing the return movement of the knife to the pattern comprises a ratchet segment 60 fixed to the plate 10 and a pawl 62 pivoted on the carrier 12 and actuated by a spring 64 to move it into engagement with the teeth of the ratchet segment 60 to hold the plate 10 against movement towards the sole. The pawl 62 is moved away from the

ratchet teeth 60 during the operation of the machine by an arm 66 pivoted on the carrier 12 and operated by a spring 68 which is stronger than the pawl spring 64. The pawl 62 has an arm 70 which carries a pin 72 extending through a slot 74 in a link 76. The link 76 is pivotally connected to the arm 66 by a pin 78 to which is pivoted a pawl 80 urged by a spring 82 into engagement with ratchet teeth 84 formed on a block fixed to the cam. During the last portion of the forward movement of the carrier the pawl 80 slips over the teeth 84 and during the return movement of the carrier the pawl 80 engages one of the teeth and thereby causes the arm 66 to be swung about its pivot to move the end of the slot 74 away from the pin 72 to allow the spring 64 to move the pawl 62 into engagement with one of the teeth 60 to hold the plate 10 from moving under the influence of its spring inward towards the sole. As the carrier 12 completes its return movement the knife is therefore carried away from the sole into the position shown in Figure 2. Forward movement of the carrier 12 at the beginning of the next operation relieves the thrust of the pawl 80 upon the arm 66 and allows the spring 68 to move the link 76 endwise until the end of the slot 74 engages the pin 72 and then moves the pawl 62 out of engagement with the teeth 60 to free the plate for movement towards the sole. A suitable stop pin 86 limits the swing of the arm 66 under action of its spring 68. The link 76 has fixed to it by a screw 88 a slotted plate 90 through which the pin 72 also extends and by adjusting this plate endwise and varying thus the effective length of the slot 74 the time in the return movement of the knife at which the pawl 62 engages the teeth 60 and therefore the amount of movement along the sole before the knife is removed therefrom may be varied.

The invention having been described, what we claim as new and desire to secure by Letters Patent of the United States is:

1. In a sole rounding machine wherein a knife and a pattern are relatively moveable to transfer the point of operation of the knife around the pattern, in combination, knife driving mechanism movable under momentum after being disconnected from its source of power to effect excess relative movement of the knife and the pattern to carry the point of operation of the knife past the starting point, means normally disconnected from the knife driving mechanism for reversing the direction of relative movement of the knife and the pattern, and a resiliently actuated device for connecting said means with the knife driving mechanism as the latter is disconnected from its source of power.

2. In a sole rounding machine wherein a

knife and a pattern are relatively movable to transfer the point of operation of the knife around the pattern, in combination, knife driving mechanism movable under momentum after being disconnected from its source of power to effect excess relative movement of the knife and the pattern to carry the point of operation of the knife past the starting point, means normally disconnected from the knife driving mechanism for cushioning the excess relative movement of the knife and the pattern and thereafter reversing the direction of said relative movement, and a device for connecting said means with the knife driving mechanism as the latter is disconnected from its source of power.

3. In a sole rounding machine wherein a knife and a pattern are relatively movable to transfer the point of operation of the knife around the pattern, in combination, knife driving mechanism movable under momentum to effect excess relative movement of the knife and the pattern to carry the point of operation of the knife past the starting point, means including a control member for connecting the knife driving mechanism with a source of power and for disconnecting it therefrom, means normally disconnected from the knife driving mechanism for limiting the motion of the knife past the starting point and for reversing the direction of movement of the knife, and a device rendered operative by movement of the control member in disconnecting the knife driving mechanism from its source of power for connecting said reversing means with the knife driving mechanism.

4. In a sole rounding machine wherein a knife and a pattern are relatively movable to transfer the point of operation of the knife around the pattern, in combination, knife driving mechanism movable under momentum after the knife driving mechanism has been disconnected from its source of power to effect excess relative movement of the knife and the pattern to carry the point of operation of the knife past the starting point, a spring, a clutch one member of which is connected with said mechanism, and connections between the other clutch member and the spring as the source of power is disconnected from the knife driving mechanism constructed and arranged to stress the latter during movement of the point of operation of the knife past the starting point and to reverse the direction of movement of said mechanism to effect relative retrograde movement of the knife and the pattern upon reaction of said spring.

5. In a sole rounding machine wherein a knife and a pattern are relatively movable to transfer the point of operation of the knife around the pattern, in combination, driving mechanism movable under momentum to ef-

fect further relative movement of the knife and the pattern to carry the point of operation of the knife past the starting point, a spring, a clutch one member of which is connected with said mechanism, connections between the other clutch member and the spring constructed and arranged to stress the latter during movement of the point of operation of the knife past the starting point and to reverse the direction of movement of said mechanism to effect relative retrograde movement of the knife and the pattern upon reaction of said spring, and means for gradually arresting and cushioning the said reverse movement of the knife driving mechanism.

6. In a sole rounding machine wherein a knife and a pattern are relatively movable to transfer the point of operation of the knife around the pattern, in combination, a carrier for said knife, knife driving mechanism movable under momentum after the driving mechanism has been disconnected from its source of power to effect further relative movement of the knife and the pattern to carry the point of operation of the knife past the starting point, a spring, a clutch one member of which is connected with said mechanism, connections between the other clutch member and the spring constructed and arranged to operate as the knife driving mechanism is disconnected from its source of power to stress the latter spring during movement of the point of operation of the knife past the starting point and to reverse the direction of movement of said mechanism to effect relative retrograde movement of the knife and the pattern upon reaction of said spring, and means for effecting separation of the pattern and the knife carrier during said retrograde movement.

7. In a sole rounding machine wherein a knife travels around a pattern, in combination, knife driving mechanism movable under momentum after the source of power has been disconnected from the knife driving mechanism to carry the knife past the starting point, a spring, a clutch one member of which is connected with the knife driving mechanism, and connections between the other clutch member and the spring constructed and arranged to operate as the source of power is disconnected from the knife driving mechanism to compress the spring during movement of the knife past the starting point and to reverse the direction of movement of the knife driving mechanism to return the knife to starting position upon reaction of the spring.

8. In a sole rounding machine wherein a knife travels around a pattern, in combination, knife driving mechanism movable under momentum to carry the knife past the

starting point, a spring, a clutch one member of which is connected with the knife driving mechanism, connections between the other clutch member and the spring constructed and arranged to compress the spring during movement of the knife past the starting point and to reverse the direction of movement of the knife driving mechanism to return the knife to starting position upon the reaction of said spring, said connections being arranged gradually to arrest the retrograde movement of the knife, and means for positively limiting the extent of retrograde movement of the knife.

9. In a sole rounding machine wherein a knife, after traveling around a pattern, moves past its starting point and then is given a retrograde movement, a knife support, a movable carrier upon which the knife support is movably mounted, means tending to move the knife support relatively to the carrier to hold the knife against the pattern during the travel of the knife around the pattern, means for locking the knife support to the carrier, mechanism for maintaining the locking means retracted during forward movement of the knife, and means operative during the retrograde movement of the knife to release the locking means to cause the knife to be withdrawn from the pattern.

10. In a sole rounding machine wherein a pattern and a knife are relatively movable to transfer the point of operation of the knife around a pattern and to a point beyond the starting point and thereafter to produce relative retrograde movement between the pattern and the knife, a knife support, a carrier on which the knife support is movably mounted, means tending to move the knife support independently of said relative movement to hold the knife against the pattern, means for locking the knife support to the carrier, mechanism for maintaining the locking means retracted during forward movement of the knife, and means operative during said relative retrograde movement of the knife and the pattern to release the locking means to prevent said independent movement of the knife support to cause separation of the knife and the pattern.

11. In a sole rounding machine wherein a knife travels around a pattern and is carried past its starting position by the momentum of mechanism associated with the knife, in combination, a drum connected with said mechanism, a band encircling the drum and adapted to grip the drum, a spring-actuated plunger connected with the band, and means for releasing the band from the drum when the machine is started and for causing the band to grip the drum when the machine is stopped so that excess movement of the drum operates to compress the spring and recoil of

the spring returns the knife to starting position.

12. In a sole rounding machine wherein a knife travels around a pattern, and a knife support moves past the starting point after the source of power has been disconnected from the knife support under the momentum to carry the knife, in combination, a spring, a clutch adapted to be connected with the knife support, and connections between the clutch and the spring constructed and arranged to operate as the source of power is disconnected from the knife support to compress the spring during movement of the knife past the starting point.

13. In a sole rounding machine wherein a knife travels around a pattern, and a knife support moves past the starting point after the knife support has been disconnected from the source of power under the momentum to carry the knife, in combination, a spring, a clutch adapted to be connected with the knife support, and connections between the clutch and the spring constructed and arranged to operate as the source of power is disconnected from the knife support to compress the spring during movement of the knife past the starting point and to cause the recoil of the spring to return the knife to starting position.

14. In a sole rounding machine wherein a knife travels around a pattern, in combination, a knife support movable under momentum to carry the knife past the starting point to insure complete rounding of the sole, a spring, a clutch adapted to be connected with the knife support, connections between the clutch and the spring constructed and arranged to compress the spring during excess movement of the knife and to cause the recoil of the spring to reverse the direction of movement of the knife, said connections comprising a dash pot arranged gradually to arrest the reverse movement of the knife, and means cooperating with said connections for positively limiting the extent of reverse movement of the knife.

15. In a sole-rounding machine wherein a pattern and a knife are relatively moved to transfer the point of operation of the knife forwardly around the pattern and to a point beyond the starting point of operation of the knife and then have relative retrograde movement, a carrier, means for relatively moving the carrier and pattern toward and away from each other in accordance with variations in the peripheral contour of the pattern while the point of operation of the knife is being transferred, a knife support movably mounted on the carrier, means for moving the knife support relatively to the carrier to maintain the knife and pattern in engagement while the point of operation of the knife is being transferred, means for locking the knife support to the

carrier, and means carried by the means for effecting relative movement of the carrier and the pattern constructed and arranged to render the locking means effective during the relative retrograde movement of the pattern and the knife to effect separation of the pattern and the knife.

16. In a sole rounding machine wherein a pattern and a knife are relatively movable to transfer the point of operation of the knife around the pattern and to a point beyond the starting point and thereafter to produce relative retrograde movement between the pattern and the knife, a carrier, a knife support movable relatively to the carrier, means for moving the knife support relatively to the carrier to hold the knife in engagement with the pattern, ratchet teeth on the knife support, a pawl on the knife carrier, a spring tending to move the pawl into engagement with the ratchet teeth, a stronger spring normally holding the pawl retracted, and means operative during the relative retrograde movement between the pattern and the knife for overcoming the force of the stronger spring.

17. In a sole rounding machine wherein a knife after traveling around a pattern moves past its starting point and then is given a retrograde movement, a carrier for moving the knife around the pattern, a knife support movable relatively to said carrier to maintain the knife in engagement with the pattern, means for locking the knife support to the carrier, mechanism for maintaining the locking means retracted during forward movement of the knife, and means movable during the retrograde movement of the knife to render the locking means operative to prevent inward movement of the knife support.

In testimony whereof we have signed our names to this specification.
